US00D928762S

(12) **United States Design Patent** (10) Patent No.: **US D928,762 S**
Jannard et al. (45) Date of Patent: **** Aug. 24, 2021**

(54) **ELECTRONIC DEVICE**(71) Applicant: **Red Technologies, LLC**, Irvine, CA (US)(72) Inventors: **James H. Jannard**, Las Vegas, NV (US); **Peter Jarred Land**, Los Angeles, CA (US); **Matthew Tremblay**, Laguan Beach, CA (US)(73) Assignee: **RED.COM, LLC**, Irvine, CA (US)(***) Term: **15 Years**(21) Appl. No.: **29/692,924**(22) Filed: **May 29, 2019****Related U.S. Application Data**

(62) Division of application No. 29/648,268, filed on May 18, 2018, now Pat. No. Des. 873,785.

(51) LOC (13) Cl. **14-03**

(52) U.S. Cl.

(57) **CLAIM**

The ornamental design for an electronic device, as shown and described.

DESCRIPTION

FIG. 1 is a top, front, and left-side perspective view of an electronic device;

FIG. 2 is a bottom, rear, and right-side perspective view of the electronic device of FIG. 1;

FIG. 3 is a front elevational view of the electronic device of FIG. 1;

FIG. 4 is a rear elevational view of the electronic device of FIG. 1;

FIG. 5 is a right-side elevational view of the electronic device of FIG. 1;

FIG. 6 is a left-side elevational view of the electronic device of FIG. 1;

FIG. 7 is a top plan view of the electronic device of FIG. 1; and,

FIG. 8 is a bottom plan view of the electronic device of FIG. 1.

The dot-dash broken lines represent the bounds of the claimed design while all other broken lines are direct to environment and are for illustrative purposes only; the broken lines form no part of the claimed design.
